UNITED STATES PATENT OFFICE.

DAVID M. DAILEY, OF GARY, INDIANA.

ELECTRIC BRAKE FOR AUTOMOBILES.

1,176,036.

Specification of Letters Patent. Patented Mar. 21, 1916.

Application filed June 23, 1915. Serial No. 35,967.

To all whom it may concern:

Be it known that I, DAVID M. DAILEY, a citizen of the United States, residing at Gary, in the county of Lake and State of Indiana, have invented new and useful Improvements in Electric Brakes for Automobiles, of which the following is a specification.

My invention relates to brakes and more particularly to electro-magnetically operated brakes.

The principal object of my invention is to provide an electro-magnetic braking mechanism which consists of a plurality of electro-magnets so arranged and controlled as to permit a gradual application of the brake and furthermore to insure a positive operation thereof in the event that certain of the electro-magnets become deenergized.

Another object of my invention is to provide a device of this character having guide members associated with the armature in such a manner as to prevent partial rotary movement thereof and consequent distorting or breaking of the connection between the armature and the braking element.

With these objects in view, and others of a similar nature which will appear as the invention is more fully understood, the invention consists in the features of construction and arrangement of parts hereinafter described and claimed, reference being had to the accompanying drawings, in which:

Figure 1 is a vertical central section showing my device connected to a brake element of a motor vehicle. Fig. 2 is a transverse section taken through the line A—A. Fig. 3 is a detail view of one end wall of the cylinder showing the electro-magnets attached thereto. Fig. 4 is a diagrammatical view of the circuit including the electro-magnets and the rheostat.

In the present instance I have shown my device attached to the horizontal rod of the common form of band brake as is used on motor vehicles and the like, the casing for my device being secured to the under side of a body of the vehicle.

Referring to the drawings in detail 1 designates a standard or support which is bolted or secured to the under side of the body of the vehicle in any suitable manner. Horizontally disposed upon the support 1 is a cylinder or casing 2 which is made of any suitable non-magnetic material such as brass or copper. Secured to the inner face of the

end wall 3 are a plurality of electro-magnets 4 which are horizontally disposed thereon. These electro-magnets 4 are arranged in two concentric circular series, the magnets in the inner series being arranged in close proximity to each other, the outer series being spaced about the edge of the wall for purposes hereinafter described. Arranged within the casing in proximity of the electro-magnets is an armature 5 which is of a disk formation and which is provided with radial slots or depressions 6. These slots 6 receive guide rods 7 which are secured to the inner wall of the cylinder and are longitudinally disposed thereon. The guide rods 7 are formed of non-magnetic material and may be cast with the casing or made separately therefrom and rigidly secured to the casing by any suitable means. The end portions of the guide rods 7 and those ends which are disposed adjacent the electro-magnets are provided with upwardly extending lugs 8 which act as abutments and limit the forward movement of the disk of the armature 5. Axially secured to the disk 5 and projecting through the end wall 9 of the casing 2 is a rod 10, the outer end of which is provided with a yoke 10' to receive a horizontal rod 1' of the braking mechanism.

In Fig. 4 I have shown a circuit 11 having a suitable source of energy such as a battery 12, the electro-magnets 4 being arranged in parallel. 13 represents the rheostat which permits the gradual application of the brake for varying the resistance of the circuit and consequent varying of the magnetic flux. It will be seen from the foregoing construction that when it is desired to apply the brakes the operator closes the circuit through the rheostats 13. The armature 5 being disposed within the magnetic field of the electro-magnets 5, upon energizing the magnets 4, the armature 5 is attracted thereby causing the rod 10 to move forward and actuate the horizontal rod 1' which in turn tightens the band about the hub. In providing the armature with the radial depressions adapted to move within the guideways 7 I have prevented any possible rotary movement of the armature which prevents any turning of the rod 10 and consequent distorting or breaking of the yoke 10'. The abutments 8 formed on the guide rod 7 as previously stated, limit the forward movement of the armature and prevent the armature from coming in contact

with the poles of the electro-magnets which if permitted to do so, would cause a mutual injury to the electro-magnets and the armature. In arranging the electro-magnets in 5 circular concentric series I have uniformly distributed them about the walls of the cylinder so as to obtain the maximum amount of pulling force. The outer series of magnets are arranged in spaced relation to allow 10 the guide members to be disposed adjacent the end wall of the cylinder.

I have formed a casing 2 and a guide rod 7 of non-magnetic material so as to cause the magnetic lines of force which emanate from 15 the electro-magnets to be directed to the armature 5. This prevents the casing and guide rods from absorbing the majority of the magnetic lines of force and causes the magnets to act directly upon the armature 20 in attracting the same.

It is believed that from the foregoing description the nature and advantages of the invention will be thoroughly understood without requiring a more extended explanation 25 and therefore the same has been omitted.

What is claimed is:—

1. In an electro-magnetic brake mechanism, the combination with a brake element, of a cylinder, a rod connected to said element and extending through one end wall 30 of said cylinder, an armature formed on the opposite end of said rod, said armature having depressions formed in the peripheral edge thereof, guide rods secured to the inner wall of said cylinder and coöperating with said depressions, and electro-magnets arranged within said cylinder and secured to the opposite end wall thereof.

2. In an electro-magnetic brake mechanism, the combination with a brake element, 40 of a cylinder, a rod connected to said element and extending through one end wall of said cylinder, an armature formed on the

opposite end of said rod, said armature having depressions formed in the peripheral edge thereof, guide rods secured to the inner wall of said cylinder and coöperating with said depressions, electro-magnets arranged within said cylinder and secured to the opposite end wall thereof, a circuit including said magnets in multiple, and a rheostat in said circuit.

3. In an electro-magnetic brake mechanism, the combination with a brake element, of a cylinder, a rod connected to said element and extending through one end wall of said cylinder, an armature formed on the opposite end of said rod, said armature having depressions formed in the peripheral edge thereof, guide rods secured to the inner wall of said cylinder and coöperating with said depressions, lugs formed on the inner extremities of each of said guide rods, and electromagnets arranged within said cylinder and secured to the opposite end wall thereof, said lugs adapted to limit the forward movement of said armature with respect to said magnet.

4. In an electro-magnetic brake mechanism, the combination with a brake element, of a cylinder, a rod connected to said element and extending through one wall of said cylinder, electromagnets arranged within the cylinder and secured to the opposite end wall thereof, an armature connected to one end of said rod and disposed within said cylinder, means mounted on said cylinder and coöperating with said armature for preventing circumferential movement of the latter.

In testimony whereof I affix my signature in presence of two witnesses.

DAVID M. DAILEY.
